UNITED STATES PATENT OFFICE.

FRED J. REID, OF WOOSTER, OHIO.

DESIGN FOR A LID FOR COOKING UTENSILS.

SPECIFICATION forming part of Design No. 34,212, dated March 12, 1901.

Application filed January 31, 1901. Serial No. 45,515. Term of patent 7 years.

To all whom it may concern:

Be it known that I, FRED J. REID, a citizen of the United States, residing at Wooster, in the county of Wayne and State of Ohio, have invented and produced a new and original Design for Lids of Cooking Utensils, of which the following is a specification.

My invention relates to a new and useful design for lids of cooking utensils, of which the following is a specification, reference being had to the accompanying drawings, forming a part thereof, in which—

Figure 1 is a plan view of my lid. Fig. 2 is a diametrical section thereof.

Like numerals of reference designate like parts in both views of the drawings.

As shown in the drawings, my lid comprises a circular disk 1, having a curved handle 2 thereon. The outer contour of the disk 1 consists of an annular level outer rim 3, an annular downwardly-beveled portion 4, an annular upwardly-curved portion 5, a raised

ring 6, and a plane central portion 7. A set of perforations 8 are formed in the curved ring 5, and guides or flanges 9 and 10 are formed adjacent thereto.

The essential or material features of my design are the circular disk 1, the outer contour of which is formed of a level rim 3, beveled portion 4, curved portion 5, having a set of perforations 8 on one side thereof, and the central level portion 7.

Having thus described my invention, what I claim as new, and wish to secure by Letters Patent, is—

The design for a lid of cooking utensils, substantially as shown and described.

In testimony whereof I have hereunto set my hand in presence of two subscribing witnesses.

FRED J. REID.
